UNITED STATES PATENT OFFICE.

ANTHONY FRANCIS McDONNELL, OF DUNMORE, PENNSYLVANIA, ASSIGNOR OF ONE-
THIRD TO WILLIAM ALOYISOUS QUINN, OF SCRANTON, PENNSYLVANIA.

CLOSURE FOR CONTAINERS.

Application filed April 17, 1928. Serial No. 270,750.

My invention relates more particularly to that class of closures for bottles, jars, and other rigid containers in which the bottle neck, for example, is enlarged by a peripheral 5 bead or otherwise around the mouth of the bottle, and the cap, for example, that known as the "crown" cap, which is provided with a cork or other lining in its crown to seal the mouth of the bottle, is crimped or compressed 10 to form a contracted rim bound tightly around the neck of the bottle, and secured against displacement thereon by the enlargement around the mouth of the bottle.

The crown cap has heretofore generally 15 been removed when desired by a special tool for the purpose which often distorts the cap in removal so that it cannot be used again even for temporarily closing the container, as when only part of the contents is to be used 20 at a time.

The primary object of my invention is to provide a neck for bottles, jars and similar containers so formed that the cap, when crimped or compressed thereon, as by means 25 of the ordinary crimping machines in common use, will be securely held in place against leakage and displacement, and yet can be easily removed by hand without the use of any tool, and after removal can be easily re- 30 placed on the neck for temporarily closing the container when only part of its contents have been used.

To this and other ends, my invention consists broadly of a container, for example, a 35 bottle, having a neck formed with peripherally and upwardly inclined beads or shoulders to engage inward projections, or some of the corrugations, if a crown cap, on the inside of the rim thereof and lift the cap off the 40 neck as the cap is turned, and with upwardly and outwardly inclined parts by which the rim of the cap, when crimped or contracted around the neck, is locked in place and which, when the cap is turned by hand, will act to 45 expand the rim and ease the lifting of the cap off the neck.

My invention also consists more specifically, in forming the peripherally and upwardly inclined shoulders on the upper sides 50 of beads raised around the neck of the bottle, the undersides of which when the several beads overlap, serve with the outwardly in-

clined parts of the neck, to engage the inward cap projections and lock the cap in place.

The inclined shoulders on the neck may 55 also be formed of inclined grooves in the neck.

Further the shoulders may be made in pairs converging downwardly on the neck so as to engage the inward projections on the 60 cap and lift the cap when the cap is turned in either direction.

This alternate specific construction, although claimed broadly herein, is not claimed specifically herein, as it forms the subject of 65 a separate application for patent filed by me April 17, 1928, Serial No. 270,749.

The upwardly and outwardly inclined parts to lock the crimped rim and expand the same and ease the removal of the cap 70 when lifted by the peripherally inclined shoulders, may be formed on the body of the neck intermediate the lifting shoulders, as described and claimed herein, or they may be formed by making the peripherally and up- 75 wardly inclined beads previously referred to, themselves inclined outwardly and upwardly toward the neck, the body of the neck between these upwardly expanding beads being cylind- 80 rical, instead of upwardly flaring as previously described.

This latter alternate specific construction, although claimed broadly herein, is not claimed specifically herein as it forms the subject of a separate application for patent 85 filed by me April 17, 1928, Serial No. 270,748.

My invention also consists in forming the inward projections, in the form of corrugations on the crown cap, with upwardly and peripherally inclined depressions to accommodate the inclined lifting shoulders on the neck against which the corrugations abut, as distinguished from those corrugations which properly engage and ride on the shoulders.

My invention also consists in forming the 95 inward corrugations on the cap with vertical depressions extending to the top thereof to soften their action against the abutting shoulders on the neck.

My invention also comprises other features 100 which will be hereinafter described and claimed.

In order that my invention may be fully understood, I shall first describe in detail the

mode in which I at present prefer to carry the invention into practice and then particularly point out the invention in the claims.

Reference is to be had to the accompanying drawings forming part of this application in which like parts are designated by the same numbers in all the figures.

Figure 1 is a sectional side view of one form of bottle closure embodying my invention, taken on the line 1—1, Figure 2.

Figure 2 is a cross-sectional view of the same on the line 2—2, Figure 1.

Figure 3 is a side view of the improved bottle neck shown in Figures 1 and 2.

Figure 4 is a perspective view of the cap shown in Figures 1 and 2.

Figure 5 is a sectional side view of another bottle closure embodying my invention, taken on line 5—5, Figure 6.

Figure 6 is a cross-sectional view of the same on the line 6—6, Figure 5.

Figure 7 is a side view of the improved bottle neck shown in Figures 5 and 6.

Figure 8 is a sectional side view of another form of bottle closure embodying my invention, taken on the line 8—8, Figure 9.

Figure 9 is a cross-sectional view of the same on the line 9—9, Figure 8.

Figure 10 is a side view of the improved bottle neck shown in Figures 8 and 9.

The invention will be described in detail as applied to a bottle, as shown in the drawings, although as primarily stated it is applicable as well to jars or similar receptacles or containers.

The bottle shown in the drawings is designed to be sold by the makers, as a new and useful article of manufacture, to bottlers of beverages and others, who purchase caps therefor, such as crown caps which are sold by cap makers and others independently, and secure the caps to the bottles by means such as the capping machines in common use.

The improved bottle shown is designed particularly for crown caps, but may be used with any other suitable cap having a rim adapted to be crimped or otherwise contracted around the neck of the bottle and provided with internal projections which will engage the inclined lifting shoulders on the cap-expanding neck.

Referring first to Figures 1, 2, 3, and 4, the cap-lifting shoulders 11 are here illustrated as formed on the upper side of beads 12 formed on the neck and inclined peripherally and upwardly toward the mouth 13 of the bottle.

The beads 12 are here shown by preference overlapping so as to form therebetween grooves 14, between which some of the internal corrugated projections 15 on the rim 16 of the crown cap here illustrated, enter when the rim is crimped or contracted thereon, so that when the cap is turned by hand, the projections 15 on the rim will ride upward on

the inclined shoulders 11, and lift the cap off the neck. The undersides of the inclined beads 12 which form the upper sides of the grooves 14, act to lock the cap in place when crimped or contracted thereon, and also to depress and secure the cap on the neck, after removal, when turned down on the same temporarily by the user to seal the mouth, as when only part of the contents of the bottle has been used and the remainder is to be covered.

Additionally to lock the cap on the neck when crimped or contracted thereon, and to ease its lifting and removal by the shoulders 11, when turned, the body of the neck between the beads 12 is here illustrated as flaring upwardly and outwardly, so that the upwardly and outwardly inclined parts formed thereby will secure the cap crimped or contracted around the same against accidental upward displacement, and will evenly spread the rim of the cap, and ease its removal when turned without the destructive distortion of the cap caused by the tool ordinarily used for this purpose.

To facilitate the crimping process and prevent crushing of the beads 12 thereby, I prefer to form the interior corrugations 15 of the crown cap when used, with inclined transverse depressions 17 to correspond with and accommodate the particular beads 12, with which the corrugations 15 do not properly engage, but against which the corrugations 15 abut.

I also prefer to form the cap corrugations with vertical depressions 17' continued to their top to soften the corrugations and ease their action on abutting beads.

In Figures 5, 6, and 7 I have shown as another embodiment of my broad invention, the body 18 of the neck 19 of the bottle cylindrical and formed with beads 20 whose upper sides 21 form the peripherally and upwardly inclined projection-engaging and cap-lifting shoulders, and whose outer sides 22, are inclined outwardly and upwardly toward the mouth 23 of the bottle, so as to form the upwardly and outwardly inclined parts, around which the rim 24 of the crown cap 25, when crimped or contracted, will be locked securely in place, and which will ease the lifting and removal of the cap and save the destructive distortion thereof as previously described in connection with Figures 1, 2, 3, and 4.

This specific form of my invention, as previously stated, is specifically claimed in a separate application for patent filed by me April 17, 1928, Serial No. 270,748.

In Figures 8, 9, and 10, I have shown another specific form of my broad invention in which the peripherally and upwardly inclined cap-lifting shoulders 26 are formed in pairs converging downwardly from the mouth of the bottle so that some of the inward corrugations 27 of the crown cap, here

illustrated for example, when crimped around this form of neck, will enter between the converging pairs of shoulders 26 and when the cap is turned in either direction, 5 the corresponding ones of the pairs of converging shoulders 26 will engage the cap projections 27, and lift and remove the cap from the neck. The parts 28 of the neck between the downwardly converging pairs of 10 shoulders 26, and the parts 29 of the neck also, between the upwardly converging shoulders 26, are flared or inclined outwardly and upwardly, so as to lock the cap on the neck when crimped and ease its removal when 15 turned and lifted as before described.

I prefer to make the converging shoulders 26, deeper at the bottom as shown where the initial greatest resistance to removal is met, and to lessen their depth gradually as they 20 approach the mouth, to make a better finish.

As previously stated, the specific form of my broad invention, shown in Figures 8, 9, and 10 is described and claimed specifically in another application for patent filed by 25 me April 17, 1928, Serial No. 270,749.

It is evident that other variations may be made in the specific performance of my broad invention without departing from the boundaries thereof as defined by the following 30 claims.

I claim as my invention:

1. A bottle or other container having its neck formed with shoulders inclined peripherally and upwardly toward the mouth to be 35 engaged by inward projections on the rim of the cap and lift the same when turned and with parts inclined outwardly and upwardly toward the mouth to engage and lock the rim of the cap when contracted around the neck 40 and to expand the rim when lifted by the inclined shoulders.

2. A bottle or other container in accord with claim 1, in which the inclined shoulders are formed by the upper sides of beads raised 45 around the neck of the bottle.

3. A bottle or other container in accord

with claim 1, in which the inclined shoulders are formed by the upper sides of overlapping beads, the lower sides of which serve also as shoulders to engage the inward projections 50 on the cap rim and lock the cap on the neck in co-operation with the upwardly and outwardly inclined parts around which the rim is contracted.

4. A bottle or other container in accord 55 with claim 1, in which the upwardly and outwardly inclined parts are formed by the upwardly and outwardly flaring body of the neck between the upwardly and peripherally inclined shoulders. 60

5. A bottle or other container in accord with claim 1, in combination with a cap having a rim to be contracted around the upwardly inclined shoulders and outwardly inclined parts, said rim having inward projections to engage the upwardly inclined shoulders and outwardly inclined parts so as to lift the cap and expand the rim when the cap is turned. 65

6. A bottle or other container in accord 70 with claim 1, in combination with a cap having a rim to be contracted around the upwardly inclined shoulders and outwardly inclined parts, said rim having inward corrugations to engage the inclined shoulders and 75 outwardly inclined parts, the inward corrugations being formed with inclined transverse depressions to accommodate the abutting inclined shoulders.

7. A bottle or other container in accord 80 with claim 1, in combination with a cap having a rim to be contracted around the upwardly inclined shoulders and outwardly inclined parts, said rim having inward corrugations to engage the upwardly inclined 85 shoulders and outwardly inclined parts, the inward corrugations being formed with depressions rising to their top to ease their action on the inclined shoulders.

In testimony whereof I affix my signature.

ANTHONY FRANCIS McDONNELL.
